UNITED STATES PATENT OFFICE

165,359

DISPLAY RECEPTACLE

Samuel Braun, Rockville Centre, and Max Crystal,
Forest Hills, N. Y., assignors to Braun-Crystal
Mfg. Co., Inc., Middle Village, N. Y., a corpora-
tion of New York

Application January 23, 1950, Serial No. 7,417

Term of patent 14 years

(Cl. D30—5)

To all whom it may concern:

Be it known that we, Samuel Braun and Max Crystal, both citizens of the United States, and residents, respectively, of Rockville Centre, Nassau County, State of New York, and Forest Hills, Queens County, State of New York, have invented a new, original, and ornamental Design for a Display Receptacle, of which the following is a specification, reference being had to the accompanying drawings, forming part hereof and in which:

Fig. 1 is a front view of a display receptacle, showing my new design.

Fig. 2 is a side elevational view.

Fig. 3 is a bottom edge view.

Fig. 4 is a top edge view.

Fig. 5 is a back view.

Fig. 6 is a front view with the cover in an opened position; and

Fig. 7 is a bottom edge view thereof in an opened position with a portion broken away.

The dominant features of my design resides in the portions shown in full lines.

We claim:

The ornamental design for a display receptacle, substantially as shown.

SAMUEL BRAUN.
MAX CRYSTAL.
